UNITED STATES PATENT OFFICE.

DAVID HOESA GOOD, OF KANSAS CITY, MISSOURI, ASSIGNOR OF ONE-THIRD TO
DAVID C. LANE, OF KANSAS CITY, MISSOURI.

AIRSHIP.

Application filed October 10, 1925. Serial No. 61,738.

My invention relates to aircraft comprising characteristics common to heavier than air and also to lighter than air vehicles of well known form, together with new, novel and improved features of invention, which in their combined form provide an airship suitable for commercial and military purposes.

In the invention longitudinally extending cages, pontoons or the like are suspended from and carried by a frame-like series of transverse supporting units including a plurality of gas bags arranged in series as further explained; together with mechanical means for propelling and for auxiliary lifting and descending purposes in combination with said gas bags.

It will be further shown that plane elements are arranged to function with coordinate mechanical elements to assist in such lifting and descending features.

Further objects of the invention will be disclosed during the description of the drawings in which Fig. 1 is a side view showing my improved airship, vertical sections being removed for purposes of illustration. Fig. 2 is a sectional view taken along the lines II-II, Fig. 1 looking in the direction of the arrows. Fig. 3 is a plan view of the airship seen in Fig. 1 omitting the gas bag and supporting frame elements therein disclosed. Fig. 4 shows an enlarged plan view of the controlling plane devices seen in Figs. 1, 2 and 3. Fig. 5 is a side view of Fig. 4 with parts removed for simplicity of detail. Fig. 6 is an enlarged plan view in section of a unit combination of the propeller shafts, gears, bearings, mountings and allied parts disclosed in Fig. 1 and operable in the longitudinal axis of the airship. Fig. 7 shows a detail assemblage of any one of the plurality of motor driven worm gear mechanisms operable for occasioning turning movements of the housing members whereby propellers of the various units may be positioned at desired positions for the purposes of the invention. Fig. 8 is a fragmentary sectional view on line 8-8 of Fig. 3. Fig. 9 is a fragmentary section on line 9-9 of Fig. 3. Similar numerals of reference indicate corresponding parts throughout all the figures of the drawings.

Referring to the drawings, at 10 and 10 are seen a pair of longitudinally extending cages, spaced apart a desired distance.

These cages may be cabs or boats as desired. Beneath these cages at intervals are seen a plurality of coiled springs 11 for cushioning landings, and also for equalizing the stresses imposed upon the bottoms of said cages when landing upon uneven ground.

Rigid with the paired cages 10 and 10 are transversely arranged at spaced intervals apart, a plurality of structural frame units of substantially A-shape, including two base or leg elements 12, 12, a cross tie 13 and two upper pieces inclined towards each other; these tie pieces 14, 14 join together at the apex 15.

Between any pair of adjacent A-frames 10 will be noted an upper gas bag 16 whose opposite ends are secured to points 15 of said A-frames as seen in Fig. 1. This gas bag 16 is longitudinally disposed in the vertical axis of the airship. Arranged below and on either side of a bag 16 are two other gas bags 17 and 18 whose ends are secured at the end connections 19, 19 and 20, 20 respectively of the tie bars 13, 13 of the said A-frames. By means of cables 16^A the gas bags are secured to each other and to the cages. The gas bags are preferably filled with helium gases and to normally have a lifting value equivalent to from 80 to 90 per cent. of the total dead and live loads of the airship and contents.

It will be seen that an airship is thus provided which in itself will not have sufficient lifting qualities to rise; by auxiliary means, power operating and mechanically functioning, I enable the craft to create additional buoyancy and lifting qualities to enable it to rise vertically and be driven horizontally or otherwise as desired. This gives characteristics of stability and safety not provided by a strictly heavier than air device.

In combination with the foregoing described elements, I combine a longitudinal series of plane elements which are arranged below the gas bags, transverse to the vertical longitudinal axis of the ship and alternating with said plane elements are arranged a longitudinal series of propeller devices. These will now be described.

At 21 is a shaft member transversely arranged and rotatable in the bearings 22 carried by the cages 10. Rigid with a shaft 21 is a centrally aligned and disposed plane member 23, the shaft 21 being attached

- rigidly to the longitudinal axis of the member 23. Cables 24 connect to the opposite side edge portions of the series of plane members 23 as seen, at 23' and 23" Fig. 5 and lead around winding drums 25 rigid with the transverse shaft 26 rotatably mounted in bearings 27 on the cages 10. A gear 38^x driven by a motor driven worm 36^x operable similar to that seen in Fig. 7, rotates the shaft 26 a measured amount whereby the plane members may be adjusted to any desired position since they can be adjusted to stop at any point of shaft rotation.
- 15 At 28 is one of a series of propeller devices previously mentioned. 29 is the propeller shaft. 30 a bevel gear carried by shaft 29 enmesh with bevel gear 31 rigid with the transverse drive shaft 32 driven by motor 33. The shaft 32 is rotatably housed in the transverse housing member 34 and turns on the roller bearings 39 arranged intermediate the member 34 and shaft 32. The member 34 is rotatable in bearings 35 on the cages 10. The worm gear 36, Fig. 7, driven by reversible motor 37 is enmesh with the gear 38 whose hub 40 is rigid with the housing 34. When the motor 37 is operated, the housing 34 may be rotated on its bearings 35 through any degree; the shaft 29 in the bearings 41 and 41^x of the gear case extension 34^x of said housing 34, will be rotated to position the propeller 28 in a desired position.
- 25 Arranged on opposite sides of the ship are a series of propellers 42 and 43. Each is provided with means for rotation to desired positions, somewhat similar to that just described for the central series of propellers 28. Thus, propeller 42 has a propeller shaft 44 carrying a bevel gear 45, meshing with a bevel gear 46 on drive shaft 47 driven by a reversible motor 48. These bevel gears are concealed within the gear case 45'. The shaft 47 being rotatably mounted within a transverse housing member 49 which in turn is revolvably mounted in bearings 50 and provided with a worm gear mechanism 51 analogous to that previously described for Fig. 7 and whereby the side propellers such as 42 may be swung through a vertical circle or arc and be positioned and retained in any swung position. The propellers 43 are operated independently of the propellers 42 by similar means and mechanisms as those just described functioning with propellers 42.
- 35 At the rear of the cages are propellers 52 and 53 driven by shafts and gearing connecting to the motors 52^x and 53^x. By means of the direction of power application these propellers 52 and 53 function in combination with rudder mechanism 55 and operate to turn the ship in a manner similar to that employed by marine vessels.

It has been previously mentioned that the gas bags transmit a lifting capacity of from 80 to 90% of the total loads. Assuming the craft on the ground; it being desired to rise vertically, the housings 34 of the central propeller devices would be rotated by prior means described, or so that the propeller shafts 29 stand vertically, with the several propellers 28 horizontally disposed or as seen in Figs. 1 and 2. The motors 33 occasion rotation of the shafts 32 and 29 to rotate the propellers 28. During this operation the cables 24 are first operated to bring the several plane surfaces 23 into the dotted vertical position 23^x Fig. 5. The propellers are so fashioned that under revolution they serve to create a condition such as will cause the aircraft, already 80-90% buoyant, to rise into the air.

When the craft has ascended to a desired height above the ground, the housings are again rotated so that the propellers assume the dotted position 28^x Fig. 1 and the planes 23 are caused to assume the positions shown in Fig. 1. The series of propellers now cause, under rotation, the craft to proceed in a forwardly direction, being similar in action to airplane propeller action. It will be seen that the air current from a forward propeller 28^x will be driven rearwardly against the under side of the planes 23 positioned as in Fig. 1 thereby creating a tendency of the ship to rise, or to compensate for the tendency of the ship to drop due to the change in position of the propellers 28 to 28^x.

During the first period, the propellers 42 and 43 are arranged as seen in Fig. 2, then swung to the dotted position 42^x, Fig. 1 to assist propellers 28^x for forward movements. To reverse the airship, the propellers 28 would assume the dotted position 28^x, Fig. 1, and the planes 23 would be turned to the dotted position 23^x, Fig. 5, and the propellers 42 and 43 reversed to a position like 43^x, Fig. 1.

To descend, the propellers 28 may be swung into the position 28^x and the plane 23 again rotated into the position 23^x.

The purpose of my invention then is to combine safety, with strength, stability and speed. Safety is primarily accomplished by using a plurality of gas bags instead of a single bag or a single bag with compartments. Under war conditions, one or more bags might be destroyed and still a safe landing or other movement effected, since the propellers 42 and 43 could be stopped, reversed or speeded up to offset the loss of a bag or bags such as would affect the equilibrium of the air-craft. These propellers therefore serve to balance the ship as well as to assist propellers 28 as previously mentioned. Making the air-craft in a series of unit sections, that is, a pair of A-frames and

three bags triangularly arranged as a single section, enables the air-craft to have a condition of some flexibility instead of calling for one of extreme rigidity. This unit arrangement also permits air ships of any desired capacity to be quickly assembled by merely adding the desired number of units. In landing the ordinary dirigible airship, it is found necessary to use extreme care in the arrangement of ballast, both dead and live. For instance, men are positioned on the cat-walk so that they may run back and forth to maintain relative desired positions of the various elements composing the dirigible. Then too, in landing ropes are dropped and an army of men must grasp these depending ropes and pull and haul to get the dirigible down. This is very objectionable; by means of my craft being only 80-90% buoyant, it would descend slowly of its own weight if all engines were stopped; while by means of the rotatable members 34 the propellers may be set as previously disclosed so as to screw the aircraft down vertically, rearwardly or forwardly, that is my airship could enter a hanger under its own power and without the necessity of using depending ropes and many men on the ground. I claim that by means of my airship, landings may be accomplished vertically or so that the airship may be brought to rest upon top of buildings, such as government postoffices and the like, as well as on landing fields.

35 The cages 10 are provided with ballast tanks 70, Fig. 9, provided with respective sea valves 71 extending through the bottoms of the cages 10, so that when additional ballast is required for any reason it is only necessary for the airship to descend to a body of water, the desired quantity of which is admitted to the tanks 70 by opening the valves 71 and 72. Ability to take on or discharge water ballast enables the air ship 40 to be maneuvered under all conditions without necessitating the loss of expensive gas from the gas bags, as heretofore required.

45 As hereinbefore pointed out, the planes 23 may be adjusted to different angles. This enables said planes 23 to fully cooperate with the propellers 42 and 43 and the water ballast in the tanks 70, in maintaining the equilibrium and the desired elevation of the ship when cruising. When the propellers 28 are adjusted forwardly to advance the air ship and the planes 23 are adjusted to the position disclosed by Fig. 1, it is evident that each plane 23 will deflect the 50 air current from the forward propeller downwardly out of the path of the following propeller, so that the latter will have relatively quiet air in which to operate and thus prove more efficient in advancing the air ship than if said following propeller op-

erated in the air current created by the forward propeller.

In emergency, the ballast tanks 70 may be filled with air so that if the aircraft were disabled and floating upon a sea or lake, 70 said ballast tanks would assist in preventing the craft from sinking.

At 73 Figs. 1 and 2 are shown the pilot cage carried by a pontoon 10. These cages 73 will be preferably entirely glass 75 enclosed, or so that visibility in all directions may be secured.

Such modifications may be employed as lie within the scope of the appended claims. Having fully described my invention, what 80 I now claim as new and desire to secure by Letters Patent is:

1. In combination in an airship; a longitudinal series of carrying gas bag elements; a longitudinal series of transverse structural frame elements as anchors for said gas bags; a longitudinal cage means carried from said structural frame elements; a plurality of propeller elements in the central longitudinal axis of the airship, a plurality of plane 90 elements in the central axis of the air ship; a plurality of propeller elements on either side of the cage elements of the airship.

2. In combination in an airship; a longitudinal series of carrying gas bags; a longitudinal series of transverse structural frame elements as anchors for said gas bags; a pair of longitudinally extending cage elements, spaced apart; a longitudinal series of power drive propeller elements, spaced at 100 intervals in the longitudinal axis of the air ship; another series of power driven elements alternating with said propeller elements as plane elements; a series of power driven elements arranged at spaced intervals 105 along the opposite outer side portions of the cage elements; and power driven propeller means and rudder means in combination at the stern of the airship.

3. In combination in an airship; a longitudinal series of carrying gas bags; a longitudinal series of transversely arranged structural frame elements as anchors for said gas bags; a pair of longitudinally extending cage elements, spaced apart, carried by said frame elements; a plurality of propeller elements at spaced intervals along the longitudinal axis of the airship and a plurality of plane elements alternating with said propeller elements; a plurality of propeller elements arranged along both sides of the airship and at spaced intervals apart; and means for rotating all of said propeller and plane elements through a vertical arc longitudinally disposed with respect to said airship and so as to create a condition of power operable propeller rotation as specified.

4. In combination as an airship; a longitudinal series of gas bag units; each unit 130

- comprising three gas bags, an upper gas bag and two lower gas bags at either side of the upper bag; a plurality of transverse frame elements at spaced intervals or so as to introduce a structural frame element as a gas bag anchorage intermediate two gas bag units; a pair of longitudinal cage elements, spaced apart, depending from said frame elements; a plurality of propeller elements at spaced intervals along the longitudinal axis of the airship and intermediate the cage elements; a plurality of plane elements also in the longitudinal axis of the airship, means for positioning said planes 10 at any angle desired; a plurality of propeller elements arranged at spaced intervals along the outer sides of the airship; shafting, gearing and motor driving means for each propeller unit; a housing for each propeller shaft and gearing unit; bearings on said cage elements within which said housings are rotatably mounted and means for rotating said housings so as to change the position of each propeller element for propeller rotation as desired.
5. In combination as an airship; a longitudinal series of gas bag units; each unit comprising three gas bags, one as an upper bag, the other two arranged below and on either side of said upper bag; a transverse structural frame intermediate a pair of gas bag units and as end anchorages for each gas bag unit section; longitudinal cage elements carried by said frame elements; the lifting capacity of said gas bags being sufficient to lift a majority of the total airship loads but not in itself sufficient to lift all of said airship loads; auxiliary mechanical means for propelling said airship and for creating through power application sufficient additional lifting capacity whereby said airship may rise vertically or otherwise as desired.
6. In combination as an airship; a longitudinal series of gas bag units; each unit comprising an upper bag and two lower bags arranged below and on either side of the upper bag; a structural A-frame element attached to each end of a gas bag unit; a pair of longitudinally extending cage elements attached to a leg of said A-frame; a plurality of propeller elements arranged at spaced intervals along the central longitudinal axis of the airship; a motor and drive shafts, gearing and propeller shaft for each propeller; a housing for said shafts, gearing and allied shaft bearings; housing bearings carried by said cages within which said housings are rotatably mounted, a motor, a worm and a worm gear cooperating with said housing means for occasioning swinging rotatable movements to the propeller shafts so that the positions of a propeller may be varied at will and as specified; a plurality of plane elements in the central longitudinal axis of the airship, a motor and worm and worm gear operating a plane shaft, said shaft being rigid with a plane member and whereby said plane member may be pivoted to a desired position; cable means linking the various plane elements together; side propeller mechanisms similar to the central propeller mechanisms and means for positioning said side propellers similar to those employed for the central propellers; rear propellers motor driven, cooperable with a rudder substantially as specified.
7. In an airship; a pair of longitudinally extending cage elements; a plurality of motor driven shaft elements transversely arranged with respect to said cages and rotatably mounted in elements carried thereby; some of said shafts having plane surfaces rigidly attached thereto for adjustable pivoted movements; some of said shafts having propeller shafts in geared connection therewith and propeller shafts mounted on said propeller shafts intermediate said cages and adjacent the plane surface; some of said shafts extending beyond the side portions of said cages and having geared connection to propeller mechanisms arranged along the side portions of said airship; all of said propeller mechanisms being mounted within housing elements, motor driven and operable to rotate to desired adjusted positions for propeller rotation in varied selected positions.
8. A unit section in airship construction comprising an upper gas bag and two lower gas bags arranged and secured intermediate two A-frame structural members and a pair of cage elements suspended from the frame members; propeller mechanisms arranged along the sides of said cages and propeller mechanisms and plane members arranged intermediate said cages and power mechanisms for rotating and position said propeller and plane members for the purposes of the invention.
9. In an airship; an upper gas bag and two lower gas bags; frame elements connecting to and depending from said gas bags; a pair of cage elements suspended from the frame members; propeller mechanisms arranged along the sides of said cages; propeller mechanisms arranged in a series intermediate said cages and plane members in series and in alternating sequence with said propellers intermediate said cages; and power mechanisms for rotating and positioning said propeller and plane members.
10. In an airship; gas bags in combination; frame elements connecting to said gas bags and depending therefrom as carrying supports; a pair of longitudinal cage elements in parallelism suspended from and carried by said supports; propeller mechanisms arranged along the sides of said

cages; propeller mechanisms and plane surfaces arranged in an alternating series with respect to each other and intermediate said cages; power mechanisms for rotating and positioning said propeller and plane members; and cushioning means on the bottom of said cage members.

11. In an airship; a pair of longitudinally extending cage members; a plurality of propeller mechanisms arranged as a longitudinal series intermediate said cage members and a plurality of plane members also intermediate said cage members, each plane member being arranged adjacent a propeller mechanism; means for pivoting a plane member so as to present a plane surface in a desired relative position to receive air currents driven thereagainst from said propeller; and means for rotating the propeller housing through 360 degrees to permit propeller rotation in a desired relative position to cooperate with said plane member in serving to tend to drive the airship in a desired direction.

12. In combination as an air ship, a longitudinal series of gas bag units, each unit comprising three gas bags, an upper gas bag and two lower gas bags at either side of the upper bag, a plurality of transverse frame elements at spaced intervals or so as to introduce a structural frame element as a gas bag anchorage intermediate two gas bag units, a pair of longitudinal cage elements spaced apart depending from said frame elements, and a plurality of propeller elements at spaced intervals along the longitudinal axis of the air ship and intermediate the cage elements.

13. In combination as an air ship, a lon-

gitudinal series of gas bag units, each unit comprising three gas bags, an upper gas bag and two lower gas bags at either side of the upper bag, a plurality of transverse frame elements at spaced intervals or so as to introduce a structural frame element as a gas bag anchorage intermediate two gas bag units, a pair of longitudinal cage elements spaced apart depending from said frame elements, a plurality of propeller elements at spaced intervals along the longitudinal axis of the air ship and intermediate the cage elements, a plurality of plane elements also in the longitudinal axis of the air ship, and means for positioning said planes at any angle desired.

14. In an airship, gas bags in combination; elements connecting to said gas bags and depending therefrom as carrying supports; a pair of longitudinally extending cage members; a plurality of propeller mechanisms arranged as a longitudinal series intermediate said cage members and a plurality of plane members also intermediate said cage members, each plane member being arranged adjacent a propeller mechanism; means for pivoting a plane member so as to present a plane surface in a desired relative position to receive air currents driven thereagainst from said propeller; and means for rotating the propeller housing to permit propeller rotation in a desired relative position to cooperate with said plane member in serving to drive the airship in a desired direction.

In testimony whereof I hereunto affix my signature.

DAVID HOESA GOOD.
